UNITED STATES PATENT OFFICE

ERNEST K. READ, OF EAST PITTSBURGH, PENNSYLVANIA, ASSIGNOR TO WESTINGHOUSE ELECTRIC & MANUFACTURING COMPANY, A CORPORATION OF PENNSYLVANIA

CONTROL RELAY FOR CIRCUIT BREAKERS

Application filed May 12, 1923. Serial No. 638,447.

My invention relates to circuit interrupter systems and more particularly to controlling devices therefor.

An object of my invention is to provide a switching system with a controlling device having a single pair of contact members, which are associated with suitable operating mechanism for controlling the complete operation of a circuit interrupter by a single manipulation of a starting switch.

Another object of my invention is to provide a circuit interrupter system with a controlling device which operates, upon an initial energization, to close the desired electrical circuit and latching mechanism, the latter being automatically tripped after the closing of the circuit interrupter.

It is a still further object of my invention to provide a controlling device for a circuit interrupter system with suitable mechanical and electrical parts for accomplishing the foregoing objects.

In the several figures of the drawing,

Figure 1 is a view, in elevation, of a panel board equipped with my improved controlling device.

Fig. 2 is a side view, in elevation, thereof.

Fig. 3 is a diagrammatic view of apparatus and circuits embodying my invention.

In the several figures of the drawing, similar reference numerals indicate like parts.

In the preferred embodiment of my invention, I provide a panel board 1, a knife switch 2, and a contactor which is indicated as a whole by the numeral 3. The contactor 3 comprises a closing coil 4, a tripping coil 5, a stationary contact member 6, and a movable contact member 7 which is mounted on a lever 8 of U-shape. The lever 8 is pivotally mounted on a pin 9, and comprises two spaced members or legs 10 preferably of brass or other non-magnetic material. A coil spring 11, which is mounted on the lever 8, is adapted to bias the contact member 7 in a clockwise direction about its pivotal support 12, as is shown in Fig. 2.

A member 13 of magnetic material, which also is pivotally mounted on the pin 9, is provided with an extension 14 which is adapted to pass between the legs of the lever 8. The

lower portion of the member 13 is provided with a tail piece 15, to which is pivotally secured a latch member 16. A notch 17 in the latch 16 is adapted for co-operation with a pin 18 which extends across the lower end of the lever 8. An extension 19 on the latch 16 is adapted for engagement with armature 21 of the tripping coil 5.

The extended portion 14 constitutes the armature member for the closing coil 4. A coil spring 22 is so placed that it bears against the inner side of the member 13 to normally retain the armature member in its outermost position.

As is shown in Fig. 3, an electric circuit 23 of any desired character is controlled by a circuit interrupter 24 comprising a pair of stationary contact members 25, a movable contact member 26, a connecting toggle mechanism 27, a closing coil 28, a tripping coil 29 and an auxiliary interlock switch 31. An operating circuit 32 is provided for supplying the system with energy.

A manually-operable switch 33, which may be located at any remote control station, comprises a pair of stationary contact members 34 and 35 and a movable contact member 36. It is to be observed that only two wires are required between the manually-operable switch 33, the contactor 3 and the circuit interrupter 24.

The panel board 1 is equipped with a suitable magnetic blowout coil 39 and arcing shields 41 which cooperate with the relatively movable contact members 6 and 7.

In the operation of a circuit interrupter system equipped with my invention, the several elements are normally in the relative positions shown in Fig. 3 and by the dot-and-dash lines in Fig. 2. The knife switch 2 is first closed. The operator then actuates the switch 33 to move the contact member 36 into engagement with the stationary contact member 35 to complete a circuit which extends from the positive side of circuit 32 through switch 33, the closing coil 4 and the right-hand blade of the knife switch 2, to the negative side of the supply circuit 32.

Upon the energization of the closing coil 4, the armature 14 is drawn in a clockwise

direction about the pin 9 and the member 13 and the tail piece 15 assume the positions shown by full lines in Fig. 2. During this movement, the notch 17 in the latch 16 engages the pin 18 and draws the lever 8 in a clockwise direction about the pin 9. During the movement of the member 13, the coil spring 22 is placed under compression.

As the lever 8 is turned about its axis, the 10 relatively movable contact members 6 and 7 are brought into juxtaposition. The movable contact member 7 is normally carried to a position in alignment with the axis of the spring 11, as is shown by the dotted lines in 15 Fig. 2. However, upon the engagement of the contact member, contact member 7 is caused to slightly turn in a counter-clockwise direction about its support 12 and thereby compress the spring 11, this position being 20 shown in full lines in Fig. 2.

The closing of the contact members 6 and 7 permits current to traverse the circuit extending from the positive side of the supply circuit 32 through the left-hand side of the 25 knife-blade switch 2, the closing coil 28 of the circuit interrupter 24, contact members 6 and 7, and the right-hand side of the knife-blade switch 2 to the negative side of the supply circuit 32. Upon the energization of 30 the closing coil 28, the circuit interrupter 24 is closed, thereby completing the circuit 23 through the stationary contact members 25 and the movable contact member 26. The auxiliary interlock switch 31 is closed simultaneously with the circuit interrupter.

The closing of the auxiliary interlock switch 31 completes a circuit extending from the positive side of the supply circuit 32 through the contact members 35 and 36 40 of the operator's switch 33, the tripping coil 5 of the control switch 3, the switch 31, and the right-hand side of the knife-blade switch 2 to the negative side of the supply circuit 32. Upon the energization of the tripping coil 5 45 its armature member 21 is drawn upwardly with a snap action which frees the pin 18 from the notch 17 in the latch 16. The position of the latch 16 at the end of the upward movement of the armature 21 is shown by 50 dash-and-dot lines in Fig. 2.

Upon the escape of the pin 18 from the notch 17, the spring 11 tends to expand causing the relatively movable contact member 7 to turn about its support 12 and to separate 55 from the stationary contact member 6. Such relative movement of the contact member tends to produce an arc which tends to blow the contact members farther apart. At the same time, the weight of the lever 8 and its 60 connected parts tends to turn the lever in a counter-clockwise direction about its axis. This combined movement interrupts the circuit through the contact members 6 and 7 65 with a resultant de-energization of the closing coil 28.

Upon the release of the manually controlled switch 33, the closing coil 4 is de-energized, the armature 14 is released and the coil spring 22 throws the member 13 in a counter-clockwise direction about its axis. The circuit through the tripping coil 5 is also interrupted by the release of the manually controlled switch 33 allowing the armature 21 and latch 16 to fall to their lower positions, whereupon the notch 17 engages the pin 18 as is shown in the dot-and-dash position in Fig. 2. The contactor 3 is again ready for the series of operations previously described.

In the event that it is desired to open the circuit 23, the operator closes the manually operable switch 33 to engage stationary contact member 34 and movable contact member 36, whereupon current traverses the circuit extending from the positive side of circuit 32, through manually controlled switch 33, the tripping coil 29, the switch 31, and the right-hand side of the switch member 2 to the negative side of the supply circuit 32. The tripping of the circuit interrupter 24 causes the opening of the switch 31, whereupon the elements of the system are again in the relative positions shown in Fig. 3.

It will, therefore, be seen that I have provided a circuit interrupter system and a controlling device therefor which consists of few parts of simple design. My controlling device removes the danger of automatic opening and closing of the circuit interrupter, termed "pumping", by reason of the fact that the operator must release the main closing coil before a subsequent operation of the device may take place.

Although I have described a specific embodiment of my invention, it will be obvious to those skilled in the art that various modifications may be made in the details of construction and arrangement of parts without departing from the principles herein set forth. I desire, therefore, to be limited only to the spirit and scope of my invention, as set forth in the appended claims.

I claim as my invention:

1. The combination with a circuit interrupter provided with a closing coil and an auxiliary interlock switch, of a switching device for controlling the circuit of the closing coil comprising a switch contact member, an operating member therefor, a connecting mechanism between said members, an operating coil for controlling operation of the operating member and a second coil controlled by the auxiliary interlock switch for controlling the effectiveness of the connecting mechanism.

2. The combination with a circuit interrupter provided with a closing coil and an auxiliary interlock switch, of a switching device for controlling the circuit of the closing coil comprising a switch in circuit with the closing coil, an operating member therefor, a

tail piece connected to said member for actuating said switch, a coil for actuating the operating member and a solenoid controlled by the auxiliary interlock switch for actuating said tail piece to disconnect the switch and the operating member.

3. The combination with a circuit interrupter provided with a closing coil and an auxiliary interlock switch, of a switching device for controlling the circuit of the closing coil comprising a switch element, an operating coil, an operating member normally in operative relation to the switch when the operating coil is first energized, and a second coil controlled by the auxiliary interlock switch for eliminating such operative relation until the first coil is de-energized.

4. The combination with a circuit interrupter provided with a closing coil and an auxiliary interlock switch, of a switching device for controlling the circuit of the closing coil comprising a switch element, an operating coil, an operating member normally in operative relation to the switch when the operating coil is first energized, a second coil controlled by the auxiliary interlock switch and means controlled thereby for controlling the operative relation between the switch and the operating member.

5. In an electrical device, a pair of coils, an armature member for each of said coils, a latching member connected to one of said armature members, a movable contact member engageable by said latching member, whereby the energization of one of said coils actuates its member, the latching member and the movable contact member, and means for selectively energizing said coils.

6. In an electrical device, a pair of coils, an armature member for each of said coils, a detachable contact member connected to said armature member, means for energizing one of said coils, whereby its armature member and the connected contact member are actuated, and means for automatically energizing the other of said coils after a predetermined operation of said device.

7. In an electrical device, a pair of coils, an armature member for each of said coils, a latching mechanism connected to said armature members, a relatively movable switch member controlled by the latching mechanism, means for energizing one of said coils whereby its armature member and the connected mechanism and switch member are actuated, and means for automatically energizing the other of said coils after a predetermined operation of said device, the energization of the second coil resulting in the release of said switch member from the control of said latching mechanism.

8. In an electrical device, a stationary contact member, a movable contact member, a coil, a pivotally mounted armature member

therefor, a tail piece mounted on said armature member, a second coil, an armature member therefor, a latching mechanism connecting said armature members, and means for energizing said coils whereby the energization of the first coil results in the actuation of the movable contact member by the armature member for the first coil and the latching mechanism, and whereby the energization of the second coil results in the tripping of said latching mechanism to release the movable contact member from the control of the armature member for the first coil.

9. In an electrical device, a stationary contact member, a movable contact member, a coil, a pivotally mounted armature member therefor, a tail piece mounted on said armature member, a second coil, an armature member therefor, a latching mechanism connecting the tail piece of said first-mentioned armature member and said movable contact member, and means for energizing said coils.

In testimony whereof, I have hereunto subscribed my name this 10th day of May, 1923.
